(57) **CLAIM**

The ornamental design for a bottle bracket, as shown and described.

DESCRIPTION

FIG. 1 is a left-side elevation view of a bottle bracket, showing my new design; the right-side elevation view being a mirror image of FIG. 1;

FIG. 2 is a front elevation view thereof;

FIG. 3 is a rear elevation view thereof;

FIG. 4 is top plan view thereof;

FIG. 5 is a bottom plan view thereof;

FIG. 6 is a top-left-front perspective view thereof;

FIG. 7 is a bottom-right-rear perspective view thereof; and, FIG. 8 is a top-left-front perspective view of the bottle bracket shown in FIG. 7, with two exemplary bottle holders affixed thereto.

The broken lines of FIG. 8 depicting bottle holders represent environmental structure that forms no part of the claimed design. The remainder of the broken lines depict portions of the bottle bracket that form no part of the claimed design.
